CLAIM

We claim the ornamental design for a packaging tray, as shown and described.

DESCRIPTION

FIG. 1 is a top perspective view of a packaging tray showing our new design;

FIG. 2 is a first bottom perspective view thereof;

FIG. 3 is a second bottom perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom plan view thereof.

(Continued)

The broken lines are shown for the purpose of illustrating parts of the article that form no part of the claim.
